UNITED STATES PATENT OFFICE.

EDWARD W. BLACKHALL, OF TORONTO, ONTARIO, CANADA, AND JOHN H. SMITH, OF BUFFALO, NEW YORK.

CASH-INDICATOR.

SPECIFICATION forming part of Letters Patent No. 425,121, dated April 8, 1890.

Application filed December 2, 1889. Serial No. 332,204. (No model.)

To all whom it may concern:

Be it known that we, EDWARD W. BLACKHALL, a citizen of Canada, residing at Toronto, in the county of York, in the Province of 5 Ontario, Canada, and JOHN H. SMITH, a citizen of the United States, residing at Buffalo, in the State of New York, have invented new and useful Improvements in Cash-Indicators, of which the following is a specification.

10

This invention relates to the cash-indicators which are used in business-houses for indicating and verifying the cash transactions between the purchasers and the attendants or clerks, and more especially to such devices in which checks are employed representing the amount of the purchases. Letters Patent of the United States, No. 346,955, were granted August 10, 1886, to J. H. Smith, 15 20 for a device of this character.

The object of our invention is to reduce the number of manipulations required in using the device and to simplify and improve the device in other respects.

25 In the accompanying drawings, Figure 1 is a front elevation of our improved cash-indicator. Fig. 2 is a top plan view thereof. Fig. 3 is a central cross-section of the device. Fig. 4 is a transverse section in line $x-x$, Fig. 30 35 Fig. 5 is a fragmentary sectional elevation of the money-draw and alarm device. Fig. 6 is a fragmentary cross-section through one of the check-display pockets. Fig. 7 is a fragmentary rear elevation, partly in section, of the locking-bar and adjacent parts.

35 Like letters of reference refer to like parts in the several figures.

The casing of the device consists of an upright rear portion A and a forwardly-projecting horizontal portion A'.

40 b represents a series of vertical check-receptacles or display-pockets arranged side by side in the upper part of the upright portion of the casing, and having their front sides 45 constructed of glass or other transparent material, so that the checks placed in the pockets will be exposed to view.

45 In the top of the upright portion A and above the pockets is arranged a vertical slot 50 or opening, through which the checks are inserted in the pockets. This slot or opening

is preferably provided with a metallic plate B, having narrow passages or slots b' corresponding in number with the number of pockets. The plate B projects a short distance 55 above the top of the casing, and the slots b' are widened or made flaring at their mouth to facilitate the insertion of the checks. The slots or passages b' are made of the proper width and thickness to permit the insertion 60 of but a single check at a time.

The lower ends of the display-pockets are closed by a transverse gate or movable bottom plate c, which extends across the lower ends of all the pockets, and slides with its 65 ends in suitable ways or ledges c', secured to the under side of a division-plate C. The latter separates the upper and lower portions of the upright part A of the casing, as represented in Fig. 4.

70 The gate or bottom plate c is held in a closed position by spiral springs d, secured at one end to the division plate C, and at their opposite ends to a depending flange d', formed at the rear edge of the gate. The display-pockets b are preferably made larger in width than the passages b', as shown in Figs. 3 and 6, so as to form shoulders or offsets e between the upper ends of the pockets and the bottom of the passages or slots b'. The pockets are 75 made of such depth that the upper ends of the checks placed in the pockets will be below the shoulders e. As soon as a check falls upon the bottom plate or gate c, it tilts forwardly or backwardly against the front or rear side of the pocket, bringing its upper end under one or the other abrupt shoulders in the pocket and preventing the withdrawal of the check after the same has been dropped 85 into the pocket.

90 In the drawings four check-display pockets are shown, the two right-hand ones being for the reception of checks representing cents, and the other two for checks representing dollars.

95 F represents the check-receiving compartments arranged in the upright part of the casing underneath the display pockets b, and into which the checks drop when the gate at the lower end of the pockets is opened. These 100 compartments are separated by upright partitions f, and each compartment is connected

with one of the display-pockets. Each compartment is closed at its lower end by a slide *g*, which moves in grooves or ways formed in the walls of the compartments, as shown in 5 Figs. 3 and 4.

The bottom plate of the machine is provided with holes *h*, which register with the lower ends of the several compartments, and through which the accumulated checks are 10 discharged from the machine upon opening the slides.

h' represents a horizontal locking-bar, extending across the outer ends of the several slides *g*, and whereby the slides are secured 15 against withdrawal by unauthorized attendants. This locking-bar is provided at its lower edge with outwardly-projecting hooks *h*², which engage in undercut recesses in the base plate of the machine, as represented in 20 Fig. 3, and at one of its ends with a lock or other suitable means for securing the bar in place. The back plate *h*³ of the upright rear portion *A* of the case, and which forms the 25 rear wall of the check-receiving compartments *F*, is preferably constructed of glass or other transparent material, whereby the checks deposited in these compartments can be viewed through this rear wall *h*³.

I represents the inclined check-rack arranged in front of the upright rear portion of the casing and divided into compartments, which contain the checks.

J represents the money-drawer arranged in the horizontal portion *A'* of the casing.

k is a rearwardly-projecting arm secured to the rear end wall of the money-drawer, and *k'* is a catch or pawl pivoted to the rear end of the arm *k*. The pawl *k'* is weighted, so as to hang in a vertical position, and is free to 40 move forwardly into a horizontal position, but is held against moving backwardly out of a vertical position by its weighted end striking the under side of the arm *k*. When the money-drawer is closed, its arm and pawl 45 project into the space between the innermost partitions *f* through an opening in the front wall *k*² of the upright portion of the casing, as represented in Figs. 3 and 4.

l represents an upright shifting-lever arranged in the space between the two innermost partitions *f*, and pivoted near its upper end to an arm or bracket *l'*, secured within the upper part of the casing. The upper arm of this shifting-lever bears against the depending flange of the gate or sliding bottom plate *c*, and its lower arm is provided with a shoe or foot *m*, which is arranged in the path of the catch or pawl *k'*. Upon opening the money-drawer the catch *k'* strikes the shoe *m*, throwing 55 the lower arm of the shifting-lever forwardly and its upper arm rearwardly. This movement of the shifting-lever opens the sliding gate *c*, and allows any checks which may have been placed in the display-pockets 60 to drop into the receiving-compartments below.

In opening the sliding gate *c* the springs *d*

are distended, and as soon as the pawl *k'* of the drawer has cleared the shoe of the lever the springs again close the gate, and the flange *d* of the gate bearing against the upper arm of the shifting-lever returns the latter to its former position. The upper arm of the shifting-lever is held against the flange *d* of the sliding gate by a stop *P*, secured to the bracket *l'*. Upon shutting the money-drawer the upper end of the pawl *k'* strikes the front end of the shoe and is swung into a horizontal position until it clears the rear end of the shoe, when its weighted end causes it to again 80 assume a vertical position. The ends of the shoe are curved upwardly, and the upper rear end of the pawl is inclined to facilitate the passage of the pawl under the shoe. The gate or bottom plate *c* of the display-pockets 85 is thus automatically controlled by the movement of the money-drawer, thereby dispensing with separate mechanism for operating the gate.

N represents an alarm-bell arranged in the 90 lower portion of the upright part of the casing in the space between one of the outer partitions *f* and the adjacent side wall of the case, as represented in Fig. 4.

n represents the hammer-arm of the bell 95 pivoted to a lug formed on a base-plate *n'*, secured to the bottom of the casing, as represented in Fig. 5. This hammer-arm is provided above its pivot with a nose or projection *o* and below its pivot with a foot *o'*.

p is a flat spring secured to the base-plate *n'* and bearing with its free end against the under side of the foot *o'*.

q is a weighted pawl pivoted to an arm secured to the rear wall of the money-drawer, 105 and whereby the hammer of the bell is operated. When the drawer is closed, the nose of the pawl overhangs the projection *o* of the hammer-arm, and upon opening the drawer the pawl engaging against the projection *o* 110 swings the hammer-arm forwardly, causing the foot of the hammer to depress the spring *p*. As soon as the pawl clears the projection of the hammer-arm, the spring reacts and throws the hammer rearwardly against 115 the bell, rendering an alarm. The alarm serves to remind the attendant to put a check in the display-pocket upon opening the drawer and attracts the attention of the purchaser to the manipulation of the attendant. It also 120 renders it impossible for unauthorized persons to tamper with the money-drawer without attracting attention.

The cash-checks are numbered from 0 to 9 and are used upon the decimal system—that is, if a sale of five cents is made a check bearing the figure 5 is placed in the first display-pocket to the right, and if a sale of twenty cents is made a check bearing the figure 2 is placed in the second display-pocket from the right 125 and a check bearing a cipher in the first and so on. If desired, ciphers may be painted on the inner side of the rear wall of the display-pockets to dispense with the use of cipher-

checks in recording decimal sums, such as ten cents, fifty cents, &c.

In using the device the money-drawer is first opened to deposit the money or make change, and a check or checks bearing a numeral corresponding to the amount of the sale is placed into the proper display-pocket by the attendant. The drawer is then closed, and the check remains in view in the display-pocket until the drawer is again opened, when the check drops into the corresponding receiving-compartment of the pocket, making room for the next check to be placed in the same pocket. At the close of the day's business the sums represented by the accumulated checks in the receiving-compartments are added together, and the total should agree with the amount of the cash in the drawer.

We claim as our invention—

- 20 1. The combination, with the case having one or more check-display pockets and one or more receiving-compartments connected with said pockets, of a gate or movable bottom closing the lower ends of the display-pockets, a money-drawer, and actuating mechanism connecting the gate with the money-drawer, whereby the gate is automatically opened upon opening the money-drawer, substantially as set forth.
- 25 2. The combination, with the case having one or more check-display pockets and one or more receiving-compartments connected with said pockets, of a gate or movable bottom closing the lower ends of the display-pockets, a money-drawer, and a shifting-lever operating said gate and actuated by the money-drawer, substantially as set forth.
- 30 3. The combination, with the case having one or more check-display pockets and one or more receiving-compartments connected with said pockets, of a gate or movable bottom closing the lower ends of the display-pockets, a money-drawer, and a shifting-lever operating said gate and actuated by the money-drawer, substantially as set forth.
- 35 4. The combination, with the case having one or more check-display pockets and one or more receiving-compartments connected with said pockets, of a gate or movable bottom closing the lower ends of the display-pockets, a money-drawer, a shifting-lever actuated by the money-drawer, whereby the gate is opened, and a spring whereby the gate is closed, substantially as set forth.

or more receiving-compartments connected 40 with said pockets, of a gate or movable bottom closing the lower ends of the display-pockets, a money-drawer, a shifting-lever actuated by the money-drawer, whereby the gate is opened, and a spring whereby the gate is 45 closed, substantially as set forth.

4. The combination, with the case having one or more check-display pockets and one or more receiving-compartments connected 50 with said pockets, of a gate or movable bottom closing the lower ends of the display-pockets, a money-drawer provided with a catch or pawl, and a shifting-lever operating said gate and arranged in the path of said catch or pawl, substantially as set forth. 55

5. The combination, with the case having one or more check-display pockets and one or more receiving-compartments connected with said pockets, of a gate or movable bottom closing the lower ends of the display-pockets, a money-drawer provided with a catch or pawl, and a shifting-lever operating said gate and provided at its lower end with a shoe arranged in the path of said pawl or catch, substantially as set forth. 60

6. The combination, with the casing having check-display pockets and receiving-compartments, of an alarm and a money-drawer having an actuating device, whereby the alarm is sounded upon opening the drawer, substantially as set forth. 65

Witness our hands this 29th day of November, 1889.
